LAUNDRY MACHINES

Harvey L. Windmiller, Moline, Ill., assignor to Ametek, Inc., New York, N.Y., a corporation of Delaware

Filed Nov. 9, 1962, Ser. No. 236,573

3 Claims. (Cl. 271—68)

This invention relates to laundry machines and particularly to an improved stacker for automatically stacking flatware having different lengths.

The principal object of the invention is to provide an automatic stacker for flatware that is fed from an ironing machine or other material handling machine.

Another object of the invention is to provide such an automatic stacker in which flatware of different lengths may be stacked with facility.

Still another object of the invention is to provide such an automatic stacker in which the leading end of the material is caused to drape on one side of a horizontal rack while the trailing end is caused to drape on the opposite side thereof.

Another object of the invention is to provide such an automatic stacker in which a resiliently mounted, horizontally disposed rack receives the draped flatware so that its elevation remains substantially the same as the draped work piles up on it.

Still another object of the invention is to provide such an automatic stacker in which the flatware may be directed to the stacker or bypassed therefrom.

Another object of the invention is to provide such an automatic stacker that will extend transversely across a plurality of lanes, in each of which may be provided separately adjustable stacker mechanisms fed by conveyor belt means common to all lanes.

In one aspect of the invention, an automatic flatware stacker may comprise a frame that extends transversely across a plurality of lanes, each being fed by an ironing or other machine. The frame may support spaced, parallel rolls that extend transversely across all of the lanes. The rolls may support endless conveyor belts, and belt tensioning devices may operate on the lower flight of the belts.

In another aspect of the invention, pivotally mounted finger means may be located at the end of the conveyor belt adjacent the exits of the ironing or other machines within each lane, the finger means being arranged so that in one pivotal position they cause the material passing from the corresponding ironer or other machine to be guided onto the stacker conveyor belt means, and in their other pivotal position they cause said material to bypass said stacker conveyor belt means.

In still another aspect of the invention, a resiliently mounted horizontal rack bar may be located within each lane at the delivery end of the stacker conveyor belt means for drapingly receiving the flatware.

In a still further aspect of the invention, a pivotally mounted diverter may also be located at the delivery end of the stacker conveyor belt means in each lane and it may be arranged to automatically divert the path of travel of the flatware, after a predetermined linear amount falls on one side of the rack bar, to a position such that the remainder of said material drapes over said bar and falls on the opposite side thereof.

In another aspect of the invention, a solenoid-operated valve means may be employed for actuating the diverter and it may be controlled by a plurality of adjustable contacts located along the path of travel of the stacker conveyor belt means. The arrangement is such that a pre-selected circuit including one of said contacts or switches may be energized, and when that switch and one common to all other adjustable contacts for the belts of one lane are closed, the solenoid valve means is energized, causing the pivotally mounted diverter to be located in an ineffective

2

position. The leading end of the material to be stacked closes the common switch and the selected of the adjustable switches, thereby moving the diverter to an ineffective position. However, when the trailing end of the material opens the selected adjustable switch, the solenoid valve means is de-energized and the diverter pivots to its effective position where it diverts the path of travel of the trailing end of the material to the opposite side of the stacker rack.

10 The above, other objects and novel features of the invention will become apparent from the following drawings and specification which are merely exemplary.

In the drawings:

FIG. 1 is an end elevational view of an automatic material stacker to which the principles of the invention have been applied;

FIG. 2 is a partial view showing a plurality of lanes in which separate stacker racks are shown;

FIGS. 3, 4 and 5 are schematic views of certain different positions of the pivotally mounted diverter;

FIG. 6 is a view similar to FIG. 3, showing the stacker rack loaded; and

FIG. 7 is a wiring diagram for the adjustable switches shown on the machine of FIG. 1.

25 Referring to the drawings, and particularly to FIGS. 1 and 2, the principles of the invention are shown as applied to an automatic stacking machine including a base frame 10. The frame may extend for a substantial distance across a plurality of parallel lanes, at the beginning of each of which flatware may be delivered from ironing or other machines. End plates 11 (only one being shown) may include aligned bearings for supporting rolls 12 and 13 in spaced, parallel relation. Spaced endless conveyor belts 14 (a plurality for each lane) may surround the rolls 12 and 13 within each of the lanes. Accordingly, the rolls 12 and 13 comprise a common drive means for all belts in each lane.

30 A bracket 15 extending between end plates 11 may support belt tensioning devices 16 and 17, and suitable power means (not shown) may rotate roll 12 or 13. Also mounted on bracket 15 between the lanes may be arms 18 that are pivoted on pin means 19. A pin 20 may extend between the arms 18 for each lane, and an air cylinder 21 operated by a suitable solenoid operated valve means 21A (FIG. 7) may be connected between pin 20 and a pin 22 in bracket 15. The end of arms 18 opposite those connected by pin 20 may support finger means 24 that may extend across the entrance to the conveyor belts 14 of the corresponding lane. Adjustment means 25 and 26 on arms 18 may be used to preset the finger means 24 both elevationally and transversely. The finger means 24 may include reverse elements 27. The arrangement is such that when the solenoid valve means 21A (FIG. 7) for air cylinder 21 is energized, finger means 24 is in its lower solid line position and bridges the gap between conveyor belt means 28, leading from another processing machine such as an ironer or the like, and the conveyor belts 14 within the corresponding lane being serviced by belt 28. De-energizing solenoid valve means 21A permits arms 18 to move counterclockwise around the pivot 19, lifting finger means 24 to its upper dash line position. In this position, finger means 24 causes the material from belt 28 to bypass the belt 14, and reverse elements 27 direct the material away from the belt 14.

35 Referring again to FIG. 1, a diverter 29 for each lane may be fixed to one end of an arm 30 that is pivotally mounted on a pin 31 in a bracket 32 fixed to a bracket 33 within frame 10. The opposite end of arm 30 may be pivoted to a link 34 that is connected to a rod 35 adapted to be reciprocated by an air cylinder 36 having a solenoid valve means 36A (FIG. 7). The

air cylinder 36 may be mounted on a channel member 38 that extends between the walls 11. Also supported by the channel member 38 may be a way 39 for each lane located over the corresponding belts 14 thereof. The way 39 adjustably supports switches, of which five are shown, i.e., 40, 41, 42, 43 and 44, having fingers 40', 41', 42', 43' and 44' that extend downwardly between spaces between the belts 14 of the corresponding lane.

A sub-frame member 49 may be provided with vertically aligned, horizontally spaced bearings 50 for slidably receiving vertical bars 51 spaced apart an amount equivalent to the width of a lane. A horizontal cross bar 52 may be fixed to the tops of the bars 51, and springs 53 may surround bars 51 between the bottom member 49 and a pin 54 extending through the bar 51 beneath the upper sub-frame member 49. Referring to FIG. 6, it is evident that as the layers of material build up on cross bar 52, it and bars 51 move downwardly against the action of spring 53 to maintain the top stacked layer at substantially the same elevation.

The switch 44 is a master switch and remains in a fixed position along way 39. Switches 43, 42, 41 and 40 are preset along way 39 to a position such that the distance between their fingers 43', 42', 41', 40' and finger 44' of master switch 44 is approximately half the length of the article of flatware that rides along belts 14 and is to be stacked on bar 52. For example, assume that a piece of material twice as long as the distance between fingers 44' and 40' is fed onto belts 14. As its leading edge closes the contacts of switches 40 and 44, solenoid valve means 36A is energized, moving diverter 29 to its ineffective dotted line position, causing the leading end of the material to fall vertically on the lefthand side of bar 52. When the trailing end of the piece of material effects opening of the contacts of switch 40, solenoid valve means 36A is de-energized and the diverter 29 moves to its solid line position, draping the remaining half of the material over bar 52 so that it hangs on the right side thereof.

A selector switch 55 may be mounted on a panel 56 and it may be manually operated to selectively render effective any one of switches 40, 41, 42 or 43. An "on-off" switch 57 may be provided for energizing the power means that rotates the rolls 12 and 13. This switch 57 when closed also energizes solenoid valve means 21A, lowering finger means 24 into its solid line position, bridging the gap between conveyor 28 and belts 14.

Although the various features of the improved stacking machine have been described in detail to fully disclose one embodiment of the invention, it will be evident that changes may be made in such details and certain features may be used without others without departing from the principles of the invention.

What is claimed is:

1. In a flatware article stacking apparatus, a base frame having end walls; parallel spaced rolls journaled in bearings in said end walls; endless conveyor belt means encircling said rolls, providing a receiving and a delivery end thereof; an article supporting rack means beneath the delivery end of said conveyor belt means; a way along said conveyor belt means; a first switch in said way adjacent the delivery end of said belt means; a plurality of distance switches mounted in said way, spaced various distances from said first switch toward said receiving end; means for selecting one of said distance switches; circuit means including said first switch and a selected one of said distance switches; diverting means at the delivery end of said conveyor belt means, normally in a position to divert the path of travel of an article being delivered from said conveyor belt means; means responsive to the operation of said first switch and the selected one of said distance switches by the leading end of an article on said conveyor belt means as it reaches said

first switch for actuating said circuit to move said diverting means to an ineffective position, and subsequently to an effective position when the trailing end of said article again actuates said distance switch for causing said article to be draped over said rack means with substantially half the length of said article on each side thereof.

2. In a flatware article stacking apparatus, a base frame having end walls; parallel spaced rolls journaled in bearings in said end walls; endless conveyor belt means encircling said rolls, providing a receiving and a delivery end thereof; an article supporting rack means beneath the delivery end of said conveyor belt means; a way along said conveyor belt means; a first switch in said way adjacent the delivery end of said belt means; a plurality of distance switches mounted in said way, spaced various distances from said first switch toward said receiving end; means for selecting one of said distance switches; circuit means including said first switch and a selected one of said distance switches; diverting means at the delivery end of said conveyor belt means, normally in a position to divert the path of travel of an article being delivered from said conveyor belt means; means responsive to the operation of said first switch and the selected one of said distance switches by the leading end of an article on said conveyor belt means as it reaches said first switch for actuating said circuit to move said diverting means to an ineffective position, and subsequently to an effective position when the trailing end of said article again actuates said distance switch for causing said article to be draped over said rack means with substantially half the length of the article on each side thereof; pivotally mounted finger means for leading articles onto said conveyor belt means; and means for raising and lowering said finger means to cause articles to bypass said conveyor belt means and to feed thereonto, respectively.

3. In a flatware article stacking apparatus, a base frame having end walls spaced apart sufficiently to include a plurality of separate lanes therebetween; parallel spaced rolls journaled in bearings in said end walls and extending transversely across said plurality of lanes; endless conveyor belt means in each lane encircling said rolls, providing a receiving and a delivery end thereof; separate article supporting rack means beneath the delivery end of the conveyor belt means in each lane; a way along the conveyor belt means in each of said lanes; a first switch in each way adjacent the delivery end of said belt means; a plurality of distance switches mounted in each way, spaced various distances from said first switch toward said receiving end; means for selecting one of said distance switches; circuit means including said first switch and a selected one of said distance switches; diverting means at the delivery end of the conveyor belt means of each lane, said diverting means normally being in a position to divert the path of travel of an article being delivered from the conveyor belt means of a corresponding lane; and separate means in each lane responsive to the operation of said first switch and the selected distance switch by the leading end of an article on the conveyor belt means of a corresponding lane as it reaches said first switch means for actuating said circuit to move its diverting means to an ineffective position, and subsequently to an effective position when the trailing end of said article again actuates said selected distance switch.
